Patented Aug. 1, 1922.

Inventor:

L. W. Keith

UNITED STATES PATENT OFFICE.

LEWIS WILKINS KEITH, OF GREENVILLE, SOUTH CAROLINA.

WRENCH.

1,424,202.

Specification of Letters Patent.

Patented Aug. 1, 1922.

Application filed July 16, 1921. Serial No. 485,200.

To all whom it may concern:

Be it known that I, LEWIS W. KEITH, a citizen of the United States, residing at Greenville, in the county of Greenville, State 5 of South Carolina, have invented certain new and useful Improvements in Wrenches; and I do hereby declare the following to be a full, clear, and exact description of the invention, such as will enable others skilled in 10 the art to which it appertains to make and use the same.

This invention relates to new and useful improvements in wrenches and particularly to socket head wrenches.

One object of the invention is to provide a wrench which is formed from a single length 15 of material and which includes a plurality of wrench sockets carried by arms, said arms serving as handles for the other arms, when 20 the socket heads of the latter are in play.

Another object is to provide a wrench of this character which has its socket head offset into parallel relation to the body of the arm, so that a nut may be reached which lies 25 behind an intervening part of a machine.

Other objects and advantages will be apparent from the following description when taken in connection with the accompanying drawing.

30 In the drawing:

Figure 1 is a side elevation of a wrench made in accordance with the invention, the socket heads being partly broken away.

Figure 2 is an end view of one of the 35 socket heads.

Figure 3 is an end view of the other socket head.

Referring particularly to the accompanying drawing, there is shown a metal strip 40 bent to form an angular U-shaped bar with the resulting longer arm 10 the bight 11 and the shorter arm 14. On the outer end of the arm 10 there is formed an enlarged head 12, having the angular socket 13 formed in its outer end, said socket being especially adapted 45 for engagement with nuts to apply or remove the same with relation to bolts. The

outer end of the other arm has the head 15 formed thereon, said head having the socket 16 in its outer end and extending in parallel 50 relation to the bight 11, and away from the arm 14. By reason of the length of the arm 10 and bight 11, it is easy to reach into a machine and readily engage a nut within a socket and turn the same onto or off from a 55 bolt. The sockets are of such depth that the nut will remain therein, thus permitting the operator to not only turn the nut from the bolt, but to withdraw the nut from the machine, without the usual inconvenience of 60 the nut dropping on the floor or ground.

The offset head 15 permits the easy engagement of the head 15 with a nut which is on a bolt disposed behind another machine part, and which would be impossible to reach 65 with the straight shank or arm. The fact that the socket is deep, permits the ready removal of the nut from the bolt, without dropping the same.

It will be further noted that arm 10 and 70 bight 11 each serves as a handle when one of the heads is in use to apply or remove a nut.

Furthermore, by reason of the depth of the sockets, it is easy to apply a nut in a part 75 of a machine too deep to reach with the arm and hand of the operator, by placing the nut within the socket and then passing the tool into the machine and engaging the nut on the bolt. 80

What is claimed is:

A wrench comprising a U-shaped bar having a long arm and a short arm, the long arm having a socket extending from its free end, and the short arm having a socket extending at right angles from its free end and in a direction away from the longer arm. 85

In testimony whereof, I affix my signature, in the presence of two witnesses.

LEWIS W. KEITH.

Witnesses:

JNO. C. HENRY,
J. V. TAYLOR.
